Geo. P. Kimmel

ATTORNEY.

UNITED STATES PATENT OFFICE

JOHN LEE CLARKE, OF FOREST HILLS, NEW YORK

MATCH HOLDER

Application filed March 17, 1928. Serial No. 262,347.

This invention pertains to match holders and more particularly to devices of this character which are adapted to hold match books wherein a plurality of flat stem matches are secured within a paper cover or envelope.

One of the objects of the invention is to provide, in a manner as hereinafter set forth, a device of the aforementioned character of such construction that a match book may be quickly and easily secured on same in such manner that the matches contained therein may be readily detached therefrom and drawn across the friction surface usually provided on such match books.

Another object of the invention is to provide a device of the character set forth wherein the book, when the matches therein have become exhausted, may be easily removed and a new book inserted therein.

A further object of the invention is the provision of a device of the aforementioned character which will be simple in construction, efficient in operation and which may be manufactured at low cost.

Other objects and advantages of the invention will be apparent from a study of the following specification, taken in connection with the accompanying drawings in which similar reference characters designate corresponding parts throughout the several views, and wherein:

Figure 1 is a perspective view of a preferred form of the invention showing a receptacle, adapted to contain a supply of matches, embodied therewith.

Figure 2 is a side elevation of the device showing same mounted on a wall with a book of matches positioned in the holder, and a supply of matches in the receptacle.

Figure 3 is a perspective view of a modified form of the invention, showing same mounted on the rim of an ash tray, and

Figure 4 is a perspective view of another modification wherein the device is mounted on a suitable base, such as a paper weight.

In the drawings the reference character 4 designates the holder which is adapted to receive a book of matches. The holder comprises an upstanding inclined base, shank or support 5 of metal having a rearwardly

and forwardly extending resilient loop 6 on the upper end thereof terminating in a downwardly inclined clamping arm 7, which is arranged in opposed relation to the base 5. The lower edge of the arm 7 is turned outwardly to form a lip 8. The arm 7 has its lower end positioned above the lower end of the base 5.

The lower end of the inclined base 5 is provided with a vertically disposed shank 9 provided with a horizontal portion 10 disposed at right angles thereto. The shank 9 provides a front wall forming portion. The horizontal portion 10 extends rearwardly to a point slightly beyond the vertical plane of the loop 6 and terminates in an upwardly turned rear wall forming portion 11, having on the upper ends of the opposite side edges thereof outwardly extending ears 12 provided with openings 13 for the passage of securing devices 14, for the purpose of anchoring the holder to a suitable base, such as the wall 15. The portion 11 opposes the shank 9.

A pair of side bars 16 extends between, and is connected to the shank 9 and portion 11 at a point remote from the horizontal portion 10, and in connection with said shank 9, and portions 10 and 11, constitute a receptacle adapted to contain a supply of matches 17. When in position on the wall, the loop 6 will be spaced from said wall to provide an opening 6' through which matches may readily be placed in or removed from, the supply receptacle.

The reference character 25 designates a book of matches detachably clamped in position and ready for use on the holder 4.

In the modified form of the invention illustrated in Figure 3, the vertical shank 9 on the base 5 is embedded in the rim 19 of an ash tray 20, said ash tray thus constituting a support for the holder.

The modified form illustrated in Figure 4 embodies a right angularly disposed horizontal foot portion 22 formed on the lower end of the shank 9, and which is provided with openings for the passage of fastening devices 23, for the purpose of securing the device 100

upon a suitable supporting base, such as a paper weight 24.

My invention is used in the following manner:

5 To insert the book of matches 25 in the holder 4, the free end or flap, of the paper cover which incloses the matches, is torn off at its point of mergence with the back of the cover. The back is then folded rearwardly 10 upon itself and the folded edge thereof is inserted under the lip 8 and forced upwardly between the base 5 and the clamping arm 7, as clearly illustrated in Figure 2, the lip 8 acting as a guide to direct the folded edge 15 of the back of the cover under said clamping arm 7. When forced upwardly the back of the cover will be securely held between the base 5 and arm 7. In this position, the outwardly turned lip 8 engages the sides of the 20 matches near the lower ends thereof and presses the same forwardly from the clamping arm 7, thus permitting a grip to be quickly and easily obtained upon the matches when it is desired to separate same from the 25 book.

In the form of the invention illustrated in Figures 1 and 2, the rearwardly inclined base 5, in conjunction with the loop 6, constitutes a partial covering for the supply receptacle. 30 By forming the loop 6 entirely to the rear of arm 7, the upper ends of the matches which are clamped on the base 5 will be free of any obstructions when it is desired to grasp one of said matches for the purpose of detaching the 35 same.

In the modified forms of the invention illustrated in Figures 3 and 4, the operation of the invention is the same as in the form shown in Figures 1 and 2, as the ash tray 20 or a paper weight 24 is shown in conjunction with the holder instead of a match-receptacle.

The holder or clip, in accordance with this invention enables a person to use book matches with one hand, as always in using 45 such matches, it is necessary to pick the book up with one hand and tear off and light the match with the other hand.

Although, as heretofore stated, that the corner is torn off, of the book, yet it is obvious 50 that it is not necessary to tear it off, merely fold it back and insert the book with the folded cover in position by sliding it downwardly and sidewise. In this way it slips in very easily and with the entire length of the cover 55 traction is held very firmly.

It is thought that the many advantages of a match holder constructed in accordance with this invention will be readily understood, and, although the preferred embodiments of 60 the invention are as illustrated and described, it is to be understood that changes in the details of construction may be made which will fall within the scope of the appended claims.

What is claimed is:

65 1. A match holder comprising a rearward-

ly inclined base having means on one end adapted to support same in an inclined position, a rearwardly and forwardly extending resilient loop on the opposite end of the base, a downwardly extending clamping arm projected from said loop and arranged in opposed relation to the base and co-operating with the latter to secure a match book thereon. 70

2. A match holder comprising a rearwardly inclined base having means on one end adapted to support same in an inclined position, a rearwardly and forwardly extending resilient loop on the opposite end of the base, a downwardly extending clamping arm projecting from said loop and arranged in opposed relation to the base said arm, at its lower end, engaging said base and co-operating with the latter to secure a match book thereon, and an outwardly extending lip on the lower end of said arm for directing the rear cover portion of the match book between the arm and the base and to maintain the upper ends of the matches contained in said book projected forwardly with respect to the arm when the book is positioned on the holder. 75 80 85 90

3. A match holder comprising a rearwardly inclined base having means on one end thereof for supporting same in an inclined position, a rearwardly and forwardly extending resilient loop on the opposite end of the base, a downwardly extending clamping arm projecting from said loop and arranged in opposed relation to the base, said clamping arm having its lower end in engagement with 95

and disposed above the corresponding end of said base and adapted to yieldingly engage the rear cover portion of a match book to secure the latter on the base, and an outwardly extending lip on the lower end of the clamping arm for directing the rear cover portion 100 of the match book between the clamping arm and the base and adapted to maintain the upper ends of the matches contained in said book projected forwardly with respect to the 105 arm when the book is positioned on the holder. 110

4. A match holder comprising a rearwardly inclined base, an integral shank formed on one end thereof at an angle thereto and adapted to support said base in an inclined position, a rearwardly and forwardly extending resilient loop on the opposite end of the base and a downwardly extending clamping arm projecting from said loop and arranged in opposed relation to the base, said clamping arm having the lower end thereof in engagement with and disposed above the corresponding end of the base, an outwardly extending lip on the lower end of the clamping arm adapted to facilitate the introduction of the rear cover portion of a match book under the clamping arm for securing said book on the base, the outer edge of said lip engaging the sides of the matches contained in the book in a manner to project the upper ends thereof 115 120 125 130

forwardly with respect to the arm when the book is positioned on the holder.

5. A match holder comprising an inclined base, a rearwardly and forwardly extending loop on the upper end thereof, a downwardly inclined clamping arm projecting from said loop and adapted to secure a match book upon the base, and a receptacle formed on the lower end of the base, said receptacle comprising a bottom having opposed front and rear walls, the latter wall having means thereon for securing same to a base, a pair of side bars extending from the front to the rear walls at the opposite side edges thereof, said receptacle constituting a support for the inclined base.

6. A match holder comprising an inclined base, a rearwardly and forwardly extending resilient loop on the upper end thereof a downwardly inclined clamping arm projecting from said loop and arranged in opposed relation to the base and co-operating with the latter to secure a match book thereon, said clamping arm having its lower end disposed above the lower end of the base, an outwardly turned lip on the lower end of the clamping arm adapted to guide the rear cover portion of the match book under the clamping arm and to engage the sides of the matches, after same are mounted on the holder, and maintain the upper ends thereof projected forwardly with respect to the clamping arm, an integral shank on the lower end of the base extending downwardly therefrom and at an angle thereto, a horizontal strip extending from the lower end of the shank and at right angles thereto, a vertical wall of greater height than the shank, formed on the rear end of horizontal strip, ears formed on the opposite side edges of the vertical wall and having openings for the passage of anchoring devices, a pair of side bars extending from the shank to the vertical wall at a point above the horizontal strip, said shank, horizontal strip, vertical wall and side bars constituting a receptacle adapted to contain a supply of matches and a support for maintaining the base in an inclined position.

7. A match holder comprising a receptacle for containing a supply of matches, an upwardly and rearwardly inclined match book supporting base mounted on the forward portion thereof, a rearwardly and forwardly extending loop on the upper end of the base, said loop, in conjunction with said base, constituting a partial covering for the receptacle, and a clamping arm carried by the loop for securing a match book on the base.

In testimony whereof, I affix my signature
60 hereto.

JOHN LEE CLARKE.
